ATTORNEY,

UNITED STATES PATENT OFFICE.

FERDINAND THIELKE, OF BROOKLYN, NEW YORK, ASSIGNOR TO THE WOODSIDE STERLING COMPANY, OF NEW YORK, N. Y.

DESIGN FOR A HANDLE FOR BUTTON-HOOKS.

SPECIFICATION forming part of Design No. 26,456, dated December 29, 1896.

Application filed November 27, 1896. Serial No. 613,704. Term of patent 7 years.

To all whom it may concern:

Be it known that I, FERDINAND THIELKE, a citizen of the United States, residing at Brooklyn, in the county of Kings and State of New York, have invented and produced a new and original Design for Handles for Button-Hooks and Like Articles, of which the following is a specification, reference being had to the accompanying drawings, in which—

Figure 1 shows a side view of my newly designed handle applied to a button-hook, and Fig. 2 a sectional view thereof on the line 2' 2 of Fig. 1.

The leading feature of my design consists of the outline as shown, the handle decreasing in width from the outer end toward the end attached to the article and having a fanciful top or outer end, decorated as shown, a shield or plain portion adjacent thereto, the outer portions thereof being decorated, scrollwork

below the latter, and the central field of the lower end plain.

A represents the fanciful top or outer end, decorated as shown, and immediately below it is the shield or plain portion B, the margin 25 thereof being decorated as shown at b.

D represents scrollwork, the handle finally ending in compound curves as shown at E and increasing in width toward the outer end A, the central field of the end E being plain and 30 bounded by the scrolls e.

What I claim is—

The design for a handle for button-hooks, and similar articles, substantially as herein shown and described.

FERDINAND THIELKE.
